UNITED STATES PATENT OFFICE.

STEPHEN H. GARST, OF DETROIT, MICHIGAN, ASSIGNOR TO THE AMERICAN HARROW COMPANY, OF SAME PLACE.

CULTIVATOR.

SPECIFICATION forming part of Letters Patent No. 621,649, dated March 21, 1899.

Application filed June 8, 1898. Serial No. 682,917. (No model.)

To all whom it may concern:

Be it known that I, STEPHEN H. GARST, a citizen of the United States, residing at Detroit, in the county of Wayne and State of Michigan, have invented certain new and useful Improvements in Cultivators, of which the following is a specification, reference being had therein to the accompanying drawings.

My invention relates more specifically to the spring-trip for cultivator-teeth; and the invention consists in the peculiar construction, arrangement, and combination of parts, as more fully hereinafter described and claimed.

15 In the drawings, Figure 1 is a side elevation of a cultivator-beam provided with my improved spring-trip. Fig. 2 is a central longitudinal section with the parts in their tripped position. Fig. 3 is a perspective view 20 of the adjustable stop.

25 A is a cultivator-beam comprising the horizontal portion *a* and the downwardly-extending substantially vertical portion *b*, preferably curved, as shown in the drawings. To the lower end of the vertical portion is hinged the tooth-section B, which preferably comprises the bifurcated shank *c*, embracing the beam and pivoted upon the pin *d*, the upper ends of the bifurcated portion having 30 the rearwardly-opening slots *e*, which engage with a stop-pin *f*.

35 C is an arm extending rearwardly from the section B, being preferably pivoted upon the pin *d* and having the lug *g* bearing against the rear face of the section B, below the pivotal point.

40 D and E are toggle-levers pivoted to each other and respectively to the arm C and pin *f*, the upper lever E being bifurcated to embrace the shank *c* and having the lugs *h* bearing upon the beam A.

45 The construction so far described has been used heretofore, a spring being provided to hold the toggles normally in a position in which they are almost locked, which spring will be overpowered when any obstacle is encountered by the harrow-tooth which might endanger the breaking of the same and will permit the tooth to trip; but in such previous 50 construction it has been generally customary to locate the spring low down upon the beam

in proximity to the toggle-levers and with its coils surrounding the pin *f*. At this point the spring will be brought into contact with the mud or moist earth, which will cover it and soon rust it out. Moreover, as but a few coils can be conveniently placed in the spring it is liable to breakage. Again, it is necessary to place a set-screw or some other adjustable stop at a point where it will limit the movement of the levers sufficiently to prevent them from absolutely locking, and this also will be covered with mud and so corroded as to often render adjustment impossible.

55 My invention relates more specifically to the spring-trip for cultivator-teeth; and the invention consists in the peculiar construction, arrangement, and combination of parts, as more fully hereinafter described and claimed.

60 It is my object to overcome those objections, which I accomplish in the following manner:

F is an arm or extension of the lever D,

which has a rearward offset, as at *i*, to clear

the beam and then extends upwardly to sub-

stantially the level of the horizontal portion

of the beam.

65 G is a coil-spring connected at one end to the upper end of the arm F and, extending forward, is secured at its opposite end to the hook or eye H on the beam.

70 I is a stop vertically adjustably secured to the arm F and adapted to strike against the rear edge of the beam to limit the movement of the toggle-levers. This stop is preferably

75 formed of the clamping-plates *j*, secured together by the bolts or screws *k*.

80 The parts being thus constructed, the trip may be set to brake back at any desired pressure by adjusting the stop I up or down on the arm F, which on account of the curved form of

85 the beam against which said stop strikes will vary the distance at which the toggles D and E stand from the dead-center line.

90 It will be observed that both the stop I and spring G are high enough above the tooth to be out of the dirt, while the spring arranged in that position may be of sufficient length to avoid all danger of overstraining it. Furthermore, the arm F being directly in rear of

95 the beam is protected thereby and forms no obstruction.

98 What I claim as my invention is—

1. The combination with the beam and a tooth-section hinged thereto, of an arm extending rearwardly from said tooth-section, a toggle-lever connection between said arm and

a point thereabove on the beam, an offset upward arm or extension of the lower member of said toggle-levers, and a horizontally and forwardly extending spring connected at one 5 end, to the upper end of said arm and at its opposite end to the beam.

2. The combination with the beam and a tooth-section hinged thereto, of an arm extending rearwardly from said tooth-section, a 10 toggle-lever connection between said arm and a point thereabove on the beam, an offset upward arm or extension of the lower member of said toggle-levers, a spring connecting the upper end of said arm with the beam, and 15 a stop vertically adjustably secured to said arm and adapted to bear against said beam.

3. The combination with the cultivator-beam, having the curved downwardly-extending end portion, the tooth-section pivoted to the lower end thereof, a spring-actuated toggle 20 for holding the tooth-section into the work, an extension therefrom beside the curved end of the beam, and an adjustable bearing for the extension against the curved beam, for the purpose described.

In testimony whereof I affix my signature in presence of two witnesses.

STEPHEN H. GARST.
